CLAIM

The ornamental design for the guitar tailpiece, as shown and described.

DESCRIPTION

FIG. 1 is a front view of a guitar tailpiece used on an exemplary electric guitar.

FIG. 2 is a perspective view of a guitar tailpiece showing my new design;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in FIG. 1 depict an exemplary environment for the guitar tailpiece and form no part of the claimed design.
